Orrville and his Atty.

UNITED STATES PATENT OFFICE.

AUGUSTUS BAUER, OF AURORA, ILLINOIS.

IMPROVEMENT IN FIRE-BOXES FOR BOILERS.

Specification forming part of Letters Patent No. 177,454, dated May 16, 1876; application filed March 30, 1876.

To all whom it may concern:

Be it known that I, AUGUSTUS BAUER, of Aurora, in the county of Kane and in the State of Illinois, have invented certain new and useful Improvements in Fire-Boxes for Boilers; and do hereby declare that the following is a full, clear, and exact description thereof, reference being had to the accompanying drawing, making a part of this specification, in which—

Fig. 1 is a perspective view of a fire-box containing my improvements. Fig. 2 is a vertical section of the same upon line xx of Fig 1, and Figs. 3, 4, and 5 are sections upon line yy of same figure, and show different methods of constructing the ledge employed for supporting the brick arch.

Letters of like name and kind refer to like parts in each of the figures.

In the use of locomotive and other boilers in which bituminous coal is burned it is necessary that the heated burning gases should be prevented from impinging directly upon the ends of the flues, and for such purpose it is customary to employ a deflector, which causes said gases to pass rearward and upward before moving in the direction of said flues. Many forms of deflector have been employed, and various kinds of material have been used for their construction, but of all heretofore known the brick arch has been found least expensive in construction and most readily adapted to the different forms of boiler.

The brick arch has, however, met with one serious difficulty that has materially interfered with its use, it having been found impracticable to provide any support for its ends upon the sides of the fire-box which would not, in a short time, be destroyed by the intense heat of the fire.

To remedy this difficulty is the design of my invention, which consists in a water fire-box for a steam-boiler, provided upon or within each of its side plates, between its crown-sheet and grate, with a support for the end of a deflecting arch, which support is formed by bending said side plates so as to form a ledge, substantially as and for the purpose hereinafter specified.

In the annexed drawing, A represents the rear end, B the front end, C and C the sides, and E the top or crown sheet, of a fire-box, which is provided with a feed-door, a , at its

said rear end, and with a number of flue-openings, b b and b , in and through the upper portion of its front end, all in the usual manner. Extending between the side plates C and C is an arch, F, which, at its front side, is placed just beneath the flues b b and b , and from thence extends rearward and upward, as shown in Fig. 2, and at each of its ends rests upon and is supported by means of a ledge, c , that is formed upon or of each of said side plates. This ledge c is, preferably, formed by corrugating the plate C, and may project inwardly, as seen in Figs. 1 and 2, or outward, as shown in Fig. 4; but, if desired, said ledge may be formed of or from a separate piece of metal, and riveted upon said plate C, over a correspondingly-shaped opening formed in the latter, as seen by the dotted lines of Figs. 1 and 3. In either event, however, water upon the outer side of said side plate will prevent injury to the said ledge by fire upon its inner side.

In cases where, from the impure character of the water employed, much sediment is deposited within the boiler, the form of ledge shown in Figs. 1 to 4 may furnish a lodgement for such sediment; in which event the form shown in Fig. 5 will best answer the desired purpose, without interference with the operation of the boiler. The ledge c last named is formed by turning the side plate C horizontally inward to the required distance, and from thence carrying said sheet downward and outward at so slight a deviation from a vertical line as to prevent such inclined portion from furnishing a lodgement for sediment.

Having thus fully set forth the nature and merits of my invention, what I claim as new is—

In combination with the fire water-box A, provided upon or within each of its side plates C with a ledge, c , the arch F extending between said plates, and resting upon and supported by said ledges, substantially as and for the purposes specified.

In testimony that I claim the foregoing I have hereunto set my hand this 22d day of March, 1876.

AUGUSTUS BAUER.
